UNITED STATES PATENT OFFICE.

EDWARD BLOUNT WINTERS, OF COFFEYVILLE, KANSAS, ASSIGNOR TO THE JOHNSON SPRING GARTER CO., OF COFFEYVILLE, KANSAS.

GARTER.

1,127,566.

Specification of Letters Patent.

Patented Feb. 9, 1915.

Application filed May 19, 1914. Serial No. 839,523.

To all whom it may concern:

Be it known that I, EDWARD B. WINTERS, a citizen of the United States, and resident of Coffeyville, in the county of Montgomery and State of Kansas, have invented certain new and useful Improvements in Garters, of which the following is a specification.

My invention relates to garters, having an inelastic leg band, and is an improvement over the forms shown and described in Letters Patent of the United States, No. 1,022,217, issued to me April 2, 1912, and in my application for Letters Patent filed March 25, 1914, Serial No. 827,116.

My invention is fully described in the following specification, of which the accompanying drawings form a part, in which the separate parts are designated by the same reference characters in each of the views, and in which:—

Figure 1 is a perspective view of a garter constructed in accordance with my present invention; Fig. 2 is a section taken on the line 2—2 of Fig. 1; and Fig. 3 is a section taken on the line 3—3 of Fig. 1.

In the drawings forming a part of this application I have shown a garter comprising an inelastic leg band a , in permanent connection, at a^2 , with one of the branches, b^2 , of a shield b , bifurcated as shown, and the other branch, b^3 , of which is provided with a hook c and the corresponding end of the leg band with a ring c^2 , for detachable connection of said shield and leg band, and it will be noted that a frictional slide a^3 is movably mounted upon the leg band and is secured to the end thereof, whereby the length of the leg band may be adjusted, this feature being of old and well known construction and may be made in any form.

Each of the branches b^2 and b^3 of the shield b is provided with a loop formed therein or secured thereto, as shown at d , to engage the corresponding angularly formed ends d^2 of a flat coil spring d^3 , the normal tendency of which is to draw the branches b^2 and b^3 toward each other, thus binding the band a to the leg of a wearer, but in an elastic manner, the strength of the spring being such as to maintain the leg band in position but without undue pressure on the

leg likely to cause congestion of blood in the leg of a wearer in the position of said band. I provide a clasp e at the lower end of the shield b adapted for detachable connection with a stocking, said clasp being held in position by means of a suitable fabric loop e^2 stitched to the shield.

The elasticity of the spring d^3 permits a considerable range of leg dimensions without the necessity for adjusting the slide a^3 , much more than is possible with elastic fabrics now commonly used, and my springs insure a permanent elasticity certainly never found in elastic fabric, resulting in a long-lived garter possessing all the usual advantages and others not heretofore known in such articles.

It will be noted that I locate the coil springs in line with the tension brought to bear thereon through the leg band, and said springs are also located at the point of greatest possible separation of the shield branches, whereby great latitude of garter expansion results, this being of particular advantage when a wearer bends his leg at the knee, and, also, for fitting legs of greater or less circumference, within certain limits, without garter adjustment.

What I claim as new, and desire to secure by Letters Patent is:—

1. A garter, comprising a bifurcated shield, a leg band in permanent connection with one branch of said shield, means for detachably connecting said leg band with the other branch thereof, said shield and leg band being composed of inelastic material, and an extension spring connected at its ends to the branches of said shield, in line with said leg band.

2. A garter, comprising a bifurcated shield, a leg band in permanent connection with one branch thereof, means for detachably connecting said leg band with the other branch thereof, said shield and leg band being composed of inelastic material, and a coil spring tending to hold said branches together and arranged in line with said leg band.

3. A garter, comprising a bifurcated shield, a leg band in permanent connection with one branch thereof, means for detach-

ably connecting said leg band with the other branch thereof, said shield and leg band being composed of inelastic material, and a flattened, extension, spring connected with 5 said branches and tending to hold the same together.

In testimony whereof I have signed my

name to this specification in presence of the subscribing witnesses.

EDWARD BLOUNT WINTERS.
